UNITED STATES PATENT OFFICE

CECIL C. MCCAIN, OF GLEN ELLYN, ILLINOIS, ASSIGNOR TO ADDRESSOGRAPH COMPANY, OF WILMINGTON, DELAWARE, A CORPORATION OF DELAWARE

PLATEN FOR PRINTING AND ADDRESSING MACHINES

Original application filed February 25, 1929, Serial No. 342,367. Divided and this application filed May 21, 1930. Serial No. 454,274.

This is a division of my application Serial No. 342,367, filed on February 25, 1929.

This invention relates to platens for printing and addressing machines and has for its object generally to provide a novel and simple sectional platen for repetitions printing of all or a certain part of a printing form, or for alternate printing of parts of the form.

The invention is applicable, for example, to an addressing machine for making impressions from printing devices which are run through the machine one at a time. A simple embodiment of these printing devices comprises a form for printing a name and a city and state address in two lines, one above the other. Many of these printing devices are provided with forms for street addresses, or for a variety of other information, but the simple form will be sufficient to illustrate the use of the invention. It may be desired to print only the name or only the address of all such simple printing devices, or it may be desired to print the name and address end to end on the same line for listing or other purposes. I have found that this can be easily accomplished and produce entirely satisfactory printing impressions by providing a sectional platen adapted to have one or the other, or both sections, set for repetitions printing, or to have the sections set for alternative printing.

Another object of the invention is to provide a device of the above described character in which the cushion plates of the platen may be attached to the platen blocks in a simple and economical manner.

The invention can be embodied with a reciprocating platen or stamping arm of the character disclosed in Patent No. 1,681,525, patented August 21, 1928, or it can be embodied with a spring or snapping platen and with a reciprocating or fixed platen, or with a stamper arm of the type disclosed in the application of Henry E. Hubbard, Serial No. 341,935, filed February 23, 1929, but I have chosen to illustrate it with a fixed platen or stamper arm as a selected embodiment of the invention and, referring to the accompanying drawing,

Fig. 1 is a side elevation showing the platen in printing position;

Fig. 2 is a front elevation:

Fig. 3 is a longitudinal section of the platen construction; and

Fig. 4 is a view taken substantially on the line 4-4 on Fig. 3.

Referring to the drawing, 4 is a fixed platen or stamper arm of an addressing machine in which printing devices are fed, one at a time, to printing position, but so far as the present invention is concerned it might just as well be a reciprocating arm. A support for the platen is illustrated in the form of a rocker 5 pivotally mounted at 6 on the platen arm. The rocker 10 is controlled by means 7 connected with a selector mechanism on the machine which causes the platen to operate or not to operate in accordance with the well understood practice. The platen comprises a skeleton head 8 secured on the support by a holding screw bolt 9 and maintained in proper position by adjusting screws 10, 10. There are two platen blocks 11 and 12 movably arranged side by side on the platen head, and these blocks are provided at their ends with cam surfaces 11' and 12'. The blocks are yieldably held in the head by springs 13 that have opposite ends attached to pins on the head and pins on the block. 80

A shaft 14 is rotatably and longitudinally movable in the platen head and has cams, such as 15, arranged thereon which engage the cam surfaces 16' and 17', and a shifter 16 is rigid on the shaft and may be integral with the cam 15, as shown, and this shifter carries two rollers 17 and 17'. A tripper 18 is pivoted at 18' on the platen arm 4 and carries a pin 19 which projects through an arcuate slot 20 in the arm and carries a washer 21 which overlaps the slot. A spring 22 is attached at one end to the pin 19 and at its other end to a pin 22' on the arm 4 at the right of the pin 19, Fig. 1. A spring 23 is attached at one end to the pin 19 and at its other end to a pin 23' on the arm 4 at the left of the pin 19, Fig. 1. The trigger hangs freely from its pivot 18', but is held normally in centered position by the springs 22 and 23 and is provided at its bottom with a foot 90

24 and a recess 25. By adjusting the shaft longitudinally the shifter will be moved into operative relation with the tripper for alternative printing or out of relation with the tripper for repetitions printing. Each of the 5 blocks 11 and 12 is provided with a longitudinal recess 26 to receive a removable plate 27 having a cushion facing 28. These plates are detachable so that they can be replaced whenever required. Spring-pressed retainers 29 are carried by the platen blocks 11 and 12 and extend through the recesses 26 and are provided with heads 30 that engage keyhole slots 31 in the plates 27. The heads 30 are adapted to enter the 10 keyhole slots when the plates are arranged to enter the longitudinal recesses 26 in the platen blocks. The heads and the walls of the keyhole slots are beveled to effect interlocking engagement of the heads with the 15 plates when the plates are moved lengthwise relative to the platen blocks in order that the plates will be snugly held in place on the blocks. The plates are provided with handles 27' to facilitate attachment with and detachment from the blocks. The shifter has an arm 32 which carries a detent 33 that is adapted to engage in a recess 34 in the end of the block 11, a recess 35 in the end of the platen block 12, or a recess 36 partly formed in the platen block 11 and partly formed in the platen block 12 to lock the shifter in position when the shaft and shifter are adjusted for causing either or both of the platens to operate. By employing this latter arrangement and properly positioning the detent in one of the openings either or both of the platen blocks may be moved downwardly into printing position.

40 The particular feature of my invention, as disclosed herein, relates to the expeditious manner in which the plates 27 may be secured to or detached from the platen blocks and, manifestly, this arrangement is such that these plates may be readily operated for either of the above arrangements.

I have shown the invention in a simple embodiment but, as indicated before, the invention is capable of embodiment in machines having reciprocating platen arms and in machines having spring or snapping platens, as well as in addressing and printing machines of many kinds, and it is to be understood that the facile manner of cushion pad carrying plate, installation or removal, may be used in connection with other types of platens or platen blocks and I reserve the right to make any changes in the invention that may be necessary or desirable within the scope of the following claims:

I claim:

1. A platen for printing and addressing machines comprising a block, a cushion plate having a slot in the back thereof, and yielding means on the face of the block for en-

gaging said slot to detachably mount the cushion plate on the block.

2. A platen for printing and addressing machines comprising a block, a cushion plate having a keyhole slot, and yielding means on the block for engaging said keyhole slot to detachably mount the cushion plate on the block.

3. The combination with a platen having a recess therein, and yieldable retaining means extending into said recess, of a plate having a cushion pad thereon, said plate having portions adapted for engagement with said retaining means to hold said plate in said recess.

4. The combination with a platen having yieldable retaining means on the face thereof, said retaining means including head portions, of a cushion plate having slots in the back thereof, said plate and head portions including cooperating sections for insuring engagement of said head portions in said slots to interlock said platen and plate.

5. The combination with a platen, of a cushion plate, and yieldable retaining means on the face of said platen, said cushion plate including portions on the back thereof for cooperation with the retaining means for connecting said cushion plate to said platen.

6. The combination with a platen having a recess, of a cushion plate having a part extendable into said recess, retaining means on said platen including spring-pressed retainers extending into said recess, said plate having slots in the face of the part thereof extendable into said recess whereby heads on said retainers may be introduced into said slots to connect said plate to said platen.

CECIL C. McCAIN.
